UNITED STATES PATENT OFFICE.

FOSTER E. PARSONS, OF MILWAUKEE, WISCONSIN.

COMBINED HOUSEHOLD IMPLEMENT.

SPECIFICATION forming part of Letters Patent No. 297,838, dated April 29, 1884.

Application filed March 25, 1884. (No model.)

To all whom it may concern:

Be it known that I, FOSTER E. PARSONS, of Milwaukee, in the county of Milwaukee and State of Wisconsin, have invented certain new and useful Improvements in Combined Household Implements; and I do hereby declare that the following is a full, clear, and exact description thereof.

My invention relates to household implements; and it consists in a combination-tool for opening fruit-jars, cutting cans, driving and drawing tacks, &c., all as will be more fully set forth hereinafter.

In the drawings, Figure 1 is a view of my combined implement in the required position for use in opening an ordinary glass fruit-jar.

Fig. 2 is a view of the said tool when employed for cutting open a metallic package, such as a sardine-box.

20 A represents the lever-handle of my device, provided with a long central longitudinal slot, *a*, having an enlarged aperture, *a'*, at one end of said slot, by means of which aperture *a'* the knife *B* is inserted to place. This knife has 25 a short central shank, *b*, and head or handle *B'*, which overlaps the edges of the said slot, while the shank *b* is square and adapted to fit pretty snugly between the walls of the slot, but which can be turned around, by reason of 30 the aperture *a'*, whenever the said knife is to be removed from or inserted within the slot. When it is in place, it can be moved longitudinally any required distance, according to the size of the can or box to be opened, as the base 35 of the blade of the knife *B* shoulders or overlaps the edges of the slot in similar manner to the head *B'*. The lever-handle *A* terminates in a screw-driver, *A'*. At the opposite end of the lever-handle, and cast or otherwise rigidly 40 formed therewith, is the curved head *C* of the implement, one end of which terminates in the tack-hammer *C'*, while the other end curves inward into a hook, *c*, and beyond that, outwardly, has the tack drawer or claw *c'*. *D* is 45 the pivot or axis of the tool when used for cutting open metallic cans or boxes, and consists of a knife or cutting-blade, preferably of a half arrow-head shape, with flat base *d*, and between the blade-base and the head *C* of the 50 tool the said blade *D* has a round shank, *d'*.

When a fruit-jar of the type shown in the drawings (and commonly called a "Mason"

jar) is to be opened, the device is applied as shown in Fig. 1 of the drawings. These jars or cans have metallic covers *E*, which screw 55 onto screw-threads formed in the glass neck of the jar, and these covers have ridges, lugs, or projections formed upon them, as shown at *e*. Then, grasping the jar with one hand and the lever-handle *A* with the other hand, 60 with the hook *c* of the curved head *C* caught over the said ridge *e*, a slight push from the person will serve to instantly turn and release the cover of the jar; and when it is designed to tighten a cover to place, (as in canning the 65 fruit, &c.,) a reverse operation to that just described will quickly and successfully accomplish the desired result.

When a metallic package is to be opened—such as a sardine-box, a tomato or fruit tin can, 70 and the like—the device is used as shown in Fig. 2—that is, the knife *D* is placed upon the top of the can at its center, and by a sharp blow driven through the metal top, and then the knife *B* (which has been adjusted the 75 required distance in the slot *a*, according to the size of opening which is desired) begins its work. The said knife has a double blade—that is, from its center to each end it is beveled on opposite sides, back of each of which 80 beveled surfaces the blade is straight—and hence it will cut either way, no matter whether the lever-handle is turned toward the operator or from the operator, the latter cut being shown in Fig. 2. The moment the lever-handle *A* 85 is turned, the pivot-blade *D* turns also on its round shank *d'*, and hence the uncut part of the can-top is clamped between the flat base *d* of the pivot-blade and the adjacent surface 90 of the curved head *C*, and thus there is no possibility of the said pivot-blade slipping from place until the circular cut is entirely completed, which is very quickly and easily done.

The operation of the tack-drawer, tack-hammer, and screw-driver parts is so obvious as 95 not to require any description, and the entire device will be found to possess great utility for every household, as well as for grocers, provision-dealers, and all persons engaged in the manufacture or sale of canned goods.

Having thus described my invention, what I claim as new, and desire to secure by Letters Patent, is—

1. In a combined household implement, the

combination of the lever-handle A, provided with the slot *a* and aperture *a'*, with the knife B, having square shank *b*, and head B', the ends of which are adapted to overlap the edges 5 of said slot, and the shank to be moved longitudinally therein, and the pivot-blade D, having flat base *d* and round shank *d'*, substantially as set forth.

2. In a combined household implement, the combination of the lever-handle A and curved head C, terminating in the hook *c*, substantially as set forth.

3. The combined household implement de-

scribed, consisting of the curved fruit-can opener, the straight lever-handle with adjustable 15 cutting-blade, the pivot-blade, and the screw-driver, tack-hammer, and tack-drawer, all as set forth.

In testimony that I claim the foregoing I have hereunto set my hand, at Milwaukee, in 20 the county of Milwaukee and State of Wisconsin, in the presence of two witnesses.

FOSTER E. PARSONS.
